UNITED STATES PATENT OFFICE

EDGAR H. BURROUGHS, OF SCARSDALE, NEW YORK, ASSIGNOR TO AMBURSEN CONSTRUCTION COMPANY, INC., OF NEW YORK, N. Y., A CORPORATION OF NEW YORK

DAM

Application filed May 27, 1930. Serial No. 455,995.

This invention relates to a novel and improved form of dam, the novel features of which will be best understood from the following description and the annexed drawings, in which I have shown a selected embodiment of the invention, and in which:—

Fig. 1 is a vertical longitudinal section through a portion of a dam illustrating one situation in which this invention is particularly applicable;

Fig. 2 is a plan view on a reduced scale, of the dam shown in Fig. 1;

Fig. 3 is a section on the line 3—3 of Fig. 1;

Fig. 4 is a horizontal sectional view 15 through the dam shown in Fig. 1 and illustrating one type of support for the water-bearing deck which may be used with advantage in the practice of this invention;

Fig. 5 is a vertical sectional view extending up- and down-stream through a dam superstructure;

Fig. 6 is a section on the line 6—6 of Fig. 5;

Fig. 7 is a view corresponding to Fig. 1, but showing a different embodiment of the invention.

The invention relates particularly to dams of the hollow type, comprising an inclined up-stream water-bearing deck 1 supported by a plurality of supports disposed beneath the deck and extending up- and down-stream. In this case, the deck is shown as of the flat slab type, but it is to be understood that by the use of the term "deck" I intend to cover any form of water-bearing surface, such, for example, as the arch and dome constructions.

The supports for the deck are preferably in the form of bents which, in Fig. 4, are shown at 2 as being of closed box form in cross section, and, in Fig. 6, they are shown at 2' as of U-shape in cross section. In either case, it is preferable that these bents shall be separated from each other by joints as indicated in both Figs. 4 and 6, and as shown at 21 in Fig. 5. It will be seen that by this arrangement, these supports have great lateral

stability throughout their length from the deck 1 to the down-stream face 3 of the dam, as they are composed of members spaced apart longitudinally of the dam and tied together. The stability lengthwise of the dam 50 may be increased by the provision of struts 4 as shown in Fig. 4, though under certain circumstances these struts may be omitted as indicated in Fig. 6. Preferably, the joints between adjacent bents are disposed substantially on surfaces of first principal stress.

Referring now to Figs. 1 and 2, I have illustrated a condition which is a vexatious one and which up to the present time has caused great difficulty. I refer to a situation where 60 there is unsatisfactory material, particularly at the ends of the dam. For example, there may be one or more faults indicated at 5 which cause the material above them to tend to slide bodily toward the stream when any 65 weight is put thereon. Such a situation is particularly bad when the dam is of substantial height, as indicated in Fig. 1. In such a situation it may be advisable to substitute for the end of the masonry dam a rock or other 70 fill 6, this full being lined or faced with concrete. However, even with such a fill, there is a substantial side or lateral thrust toward the stream which is an unknown quantity.

My invention finds particular value in 75 such a situation as that just described. Assuming the conditions illustrated in Fig. 1, I may provide at the end of the dam a buttress or retaining wall 7, here shown as having a plurality of rearwardly extending shelves 8 80 and vertical walls 9 supporting the shelves. The relation of this end buttress to the profile of the dam may be as illustrated in Fig. 3.

The rock fill will be received in the pockets formed by the walls 9 and shelves 8 and thus aid in making the end buttress independently stable. While I have shown a particular form of end buttress, it is to be understood that other forms may be adopted and that the invention is not necessarily lim- 90

ited to this particular form, the important thing being that the end buttress shall be as nearly independently stable as possible, so as to support the fill behind it. The fill will 5 extend around the down-stream face of the dam, its top being indicated in Fig. 2 at 10, and the line of contact between the fill and the down-stream face being indicated at 11, and the foot of the fill at 12. Similarly, the 10 up-stream face or deck of the dam meets the fill at the line 13. Preferably, the down-stream face of the dam will be closed so as to prevent the rock or other material from coming beneath the deck.

15 With the arrangement described above, lateral thrust may be provided against to good advantage, no matter whether this thrust is due to the rock fill or to slippage along one or more faults in the material beyond the 20 fill. Assuming that the weight of the structure and its load may be represented by the line 14 in Fig. 1 and that the horizontal thrust is represented by the line 15, then the resultant of these two forces may be represented 25 by the line 16. By providing bents of the form described hitherto which have great lateral stability and, if necessary, by using additional bracing or struts between these bents, it is possible to transmit the force 30 represented by the line 16 through the super-structure of the dam to the foundation of the supports for this part of the dam; in other words, to carry it to the foundation within a very short distance and thus to relieve the 35 greater portion of the dam superstructure from the stresses caused by this lateral thrust. By "great lateral stability" I mean a stability sufficient to take the entire thrust from the fill, if necessary, or a stability of that order, so that, in case of failure of the retaining 40 wall, each support will resist the thrust of the fill as a retaining wall.

The above may be accomplished by using 45 a structure such as that shown in Fig. 4, the struts 4 being preferably in the form of continuous walls extending between the bents and provided with vertical joints 17 between the struts and bents. These struts are preferably located in alinement with the transverse portions 50 18 of the bents so as to form in effect a continuous lateral support from the end buttress 7 out through the superstructure of the dam to a point where it may no longer be needed. In the illustrated embodiment I 55 have indicated the top of the strut walls as at 19 and extending to the support 20 adjacent the foot 12 of the fill. The extent of these bracing walls will, of course, be a matter of design for the individual job. The joints 60 between bents in the supports are shown at 21, in Figs. 1, 4, 5, and 6.

65 Referring now to Fig. 7, the invention may be practiced by omitting the fill and by carrying the buttress 2 and struts 4 clear to the end of the dam and over the

fault 5, the buttresses being preferably of the bent type referred to above. In this way, any side thrust is transmitted from the portion above the fault to the other portion of the dam, and thence to its foundation. 70

I claim:

1. A dam comprising an inclined up-stream water-bearing deck, a plurality of supports beneath said deck and extending down-stream therefrom and spaced apart 75 longitudinally of the dam, each of said supports being formed of a plurality of bents separated by joints disposed approximately parallel to a trajectory of first principal stress, an independently stable support at 80 one end of the dam, a fill behind said end support, and struts between said supports at said joints.

2. A dam comprising an inclined up-stream water-bearing deck, a plurality of supports beneath said deck and extending down-stream therefrom and spaced apart longitudinally of the dam, each of said supports being formed of a plurality of bents separated by joints disposed approximately parallel to a trajectory of first principal stress, 85 and struts between adjacent supports at said joints and adapted to transmit lateral thrust from one support to another. 90

3. A dam comprising a masonry structure 95 having an inclined up-stream water-bearing deck, a plurality of supports spaced apart lengthwise of the dam beneath said deck and extending down-stream therefrom, a fill disposed at one end of said structure and forming part of the dam, and a retaining wall extending up- and down-stream between said structure and said fill, said wall being designed to retain said fill independently 100 of the masonry structure and having an up- and down-stream profile substantially the same as that of the masonry structure 105 adjacent thereto.

4. A dam comprising a masonry structure 110 having an inclined up-stream water-bearing deck, a plurality of supports spaced apart lengthwise of the dam beneath said deck and extending down-stream therefrom, a fill disposed at one end of said structure and forming part of the dam, a retaining wall extending up- and down-stream between said structure and said fill, said wall being designed to retain said fill independently of 115 the masonry structure and having an up- and down-stream profile substantially the same as that of the masonry structure adjacent thereto, and means closing the down-stream face of the dam adjacent said wall, to 120 keep the material of the fill out of the space beneath the deck. 125

5. A dam comprising a masonry structure having an inclined up-stream water-bearing deck, a plurality of supports spaced apart lengthwise of the dam beneath said deck and extending down-stream therefrom, a fill dis- 130

posed at one end of said structure and forming part of the dam, and a retaining wall extending up- and down-stream between said structure and said fill, said wall being designed to retain said fill independently of the masonry structure and having an up- and down-stream profile substantially the same as that of the masonry structure adjacent thereto, each of said supports adjacent to the retaining wall being designed to take the thrust from said fill.

6. A dam comprising a masonry structure having an inclined up-stream water-bearing deck, a plurality of supports spaced apart lengthwise of the dam beneath said deck and extending down-stream therefrom, a fill disposed at one end of said structure and forming part of the dam, a retaining wall extending up- and down-stream between said structure and said fill, said wall being designed to retain said fill independently of the masonry structure and having an up- and down-stream profile substantially the same as that of the masonry structure adjacent thereto, each of said supports adjacent the retaining wall being designed to take the thrust from said fill, and struts extending between said adjacent supports.

7. A dam comprising a masonry structure having an inclined up-stream water-bearing deck, a plurality of supports spaced apart lengthwise of the dam beneath said deck and extending down-stream therefrom, a fill disposed at one end of said structure and forming part of the dam, a retaining wall extending up- and down-stream between said structure and said fill, said wall being designed to retain said fill independently of the masonry structure and having an up- and down-stream profile substantially the same as that of the masonry structure adjacent thereto, and means closing the down-stream face of the dam adjacent said wall, to keep the material of the fill out of the space beneath the deck, each of said supports adjacent the retaining wall being designed to take the thrust from said fill.

8. A dam comprising a masonry structure having an inclined up-stream water-bearing deck, a plurality of supports spaced apart lengthwise of the dam beneath said deck and extending down-stream therefrom, a fill disposed at one end of said structure and forming part of the dam, a retaining wall extending up- and down-stream between said structure and said fill, said wall being designed to retain said fill independently of the masonry structure and having an up- and down-stream profile substantially the same as that of the masonry structure adjacent thereto, means closing the down-stream face of the dam adjacent said wall, to keep the material of the fill out of the space beneath the deck, each of said supports adjacent the retaining wall being designed to take the thrust from

said fill, and struts extending between said adjacent supports.

9. A composite dam comprising a fill and a masonry structure disposed in line with each other, said masonry structure comprising an inclined up-stream water-bearing deck with supports disposed beneath it, and a retaining wall extending up- and down-stream between said fill and structure and designed to take the thrust of said fill independently of said structure.
